DESIGN FOR A TEXTILE FABRIC

William T. Simonton, Jr., Totowa, N. J.

Application July 28, 1938, Serial No. 78,799

Term of patent 3½ years

To all whom it may concern:

Be it known that William T. Simonton, Jr., a citizen of the United States and resident of Totowa, in the county of Passaic, State of New Jersey, has invented a new, original, and ornamental Design for a Textile Fabric, of which the following is a specification, reference being had to the accompanying drawing, forming part thereof, and in which,

The single figure of the drawing illustrates a textile fabric embodying my new design.

The design units contained between the dot-and-dash lines, which unit is repeated in regular succession as indicated by the extensions beyond the unit boundaries.

I claim:—

The ornamental design for a textile fabric, substantially as shown and described.
